UNITED STATES PATENT OFFICE.

H. K. AVERILL, JR., OF DECORAH, IOWA.

PHOTOGRAPHIC-PLATE HOLDER.

Specification forming part of Letters Patent No. **35,206**, dated May 13, 1862.

To all whom it may concern:

Be it known that I, H. K. AVERILL, Jr., of Decorah, in the county of Winneshiek and State of Iowa, have invented a new and useful Improvement in Photographic-Plate Holders; and I do hereby declare that the following is a full, clear, and exact description of the same, reference being had to the accompanying drawings, forming part of this specification, in which—

Figure 1 is a front view of a plate-holder constructed according to my invention. Fig. 2 is a back view of the same. Fig. 3 is a section taken diagonally through opposite corners of the same.

Similar letters of reference indicate corresponding parts in the several figures.

This invention consists in the construction of the plate-holder for supporting the sensitized glass or other plate in the camera, to present a series of fine points or edges for the support of the plate, the object being to prevent the collection of the sensitizing solution on the plate at the lower edge thereof and to protect the plate or picture from stains by contact with the drippings from the plate or other foreign matter that might be present on the plate-holder.

In carrying out my invention I propose to make the entire plate-holder of a single piece

of porcelain, glass, or other material that will not be acted upon by the chemicals with which it will have to come in contact. On the interior of each side I construct two or more sharp-edged projections, *a a*, whose edges run from back to front for the support of the edges of the plate, and at the back of each corner I construct supporting-points *bb*, which are turned in a forward direction to support the back of the plate.

The manner in which the plate is supported at the edges by the sharp-edged projections *a a* and at the back by the pointed projections *bb* is fully illustrated by the representation of the plate in red outline in Figs. 1 and 3, where it can be seen that there is no place in the plate-holder where any liquid or other matter can accumulate in contact with the plate.

What I claim as my invention, and desire to secure by Letters Patent, is—

The plate-holder composed of a solid frame provided with points *bb* and edges *a a*, substantially as and for the purpose herein specified.

H. K. AVERILL, JR.
